(57) **CLAIM**

The ornamental design for fitness equipment, as shown and described.

DESCRIPTION

FIG. 1 is an elevated top perspective view of a new design for fitness equipment;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is an elevated bottom perspective view thereof.

1 Claim, 8 Drawing Sheets
